UNITED STATES PATENT OFFICE

MAX BRUNNER, OF SCHWAZ, AUSTRIA

BED FASTENING-FITTING

Application filed January 18, 1931, Serial No. 508,542, and in Austria October 31, 1930.

This invention relates to improved fastening fittings for the assembling of the parts of beds. The old-fashioned fittings, which involved hollowing out the material of the bed and countersinking have in recent times become largely displaced by the so-called angle bed fittings which are merely screwed to the parts of the bed. These latter fittings consist of an angle iron screwed to the side portion 10 of the bed and provided in its standing part with tapered slots into which the heads of screws or hooks attached to the foot or head end of the bed can be inserted and held. These angle bed fittings have only a limited 15 carrying capacity, and require a large number of screws for their attachment.

The present invention provides a fitting which likewise embodies an angularly bent portion having a standing flange adapted to 20 receive hooks incorporated in the other part, but is distinguished by the essential feature that these hooks are supported by steps or gaps cut in the edge of the said flange. In 25 accordance with the invention this standing flange can be constituted by the side wall of a tray-shaped fitting which is applied with its standing edges to the one part of the bed. For the purpose of simplifying the attachment of this tray the latter may be provided 30 with projecting teeth on the portions of the edge of the flange which come in contact with the surface of the bed. During the fastening 35 of the fitting to the bed these teeth can be driven into the wood, thus enabling screws to be reduced in number and at the same time improving the hold.

An example of the carrying out of the invention is illustrated in the accompanying drawings, in which:—

40 Fig. 1 shows in section the interlock of the fittings attached to two parts of a bed.

Fig. 2 shows in perspective the two parts of the fittings, in the interlocked position.

45 Figs. 3 and 4 show in side elevation modifications of the standing flange of the one portion of the fittings.

50 Referring to the drawings the portion of the fitting to be attached to the foot or head end of the bed consists of a shallow tray 2 in the shape of a low box lid which is applied

with its standing edges to the part 1 of the bed and secured thereto by means of screws 3. The one side wall 4 of the tray is provided with excisions which interrupt its straight edge and form steps for the support of the hooks incorporated in the other portion of the fitting. This latter consists of an angle iron the side 5 of which is screwed to the side piece of the bed, and the side 7 of which is provided with hooks 8 by means of suitable 55 excisions.

When the tray 2 is applied with its edges to the surface of the bed the latter forms together with the excisions in the flange 4 slots into which the hooks 8 can be inserted until 60 they are seated on the standing portions of this flange. These standing portions can therefore have perfectly straight sides.

Three-cornered flaps or teeth 9 can be provided on the remaining standing portions 70 of the side wall 4 of the tray 2 at the sides of the gaps. These teeth are preferably pointed so that they can be driven into the wood of the bed with a light blow of a hammer when the fitting is being attached. In 75 this manner the hold of the fitting is improved and at the same time the number of fastening screws and therefore also the expenditure of labour is reduced. The slots through which the hooks 8 are passed are completely cov- 80 ered up and tightly closed by the side 7 of the angle iron, so that the harbouring of vermin is prevented.

Fig. 3 shows a form for the side wall of the tray without the teeth 9. These teeth can 85 also for example be arranged symmetrically in pairs, as shown in Fig. 4.

I claim:

1. A bed fastening fitting comprising an angular portion with a standing flange adapted for the reception of hooks, the said angular portion being the side wall of a shallow prismatic tray adapted to be attached to a portion of a bed with the standing edges of the said tray in contact with the said portion of a bed, the said side wall being provided with excisions for the formation of bearings for the said hooks on the lower edge of the said excisions, and projecting teeth on the remaining portions of the said side wall adapted to 100

be driven into the material of the said portion of a bed.

2. A bed fastening fitting comprising an angular portion with a standing flange adapted for the reception of hooks, the said angular portion being the side wall of a shallow prismatic tray adapted to be attached to a portion of a bed with the standing edges of the said tray in contact with the surface of the said portion of a bed, excisions in the said side wall for the formation of bearings for the said hooks, and projecting teeth disposed at the side of the remaining standing portions of the said side wall and adapted to be driven into the material of the said portion of a bed during the attachment of the said fitting.

3. A bed fastening fitting comprising an angular portion with a standing flange adapted for the reception of hooks, the said angular portion being the side wall of a shallow prismatic tray adapted to be attached to a portion of a bed with the standing edges of the said tray in contact with the surface of the said portion of a bed, excisions in the said side wall for the formation of bearings for the said hooks, and projecting teeth disposed in mutually symmetrical pairs at the side of the remaining standing portions of the side wall and adapted to be driven into the material of the said portion of a bed during the attachment of the said fitting.

In testimony whereof I affix my signature.
MAX BRUNNER.
